UNITED STATES PATENT OFFICE.

FREDERICK MARKWICK, OF DETROIT, MICHIGAN.

SACK-FASTENER.

1,351,958.

Specification of Letters Patent.

Patented Sept. 7, 1920.

Application filed December 11, 1919. Serial No. 343,993.

To all whom it may concern:

Be it known that I, FREDERICK MARKWICK, a citizen of the United States, residing at Detroit, in the county of Wayne and State 5 of Michigan, have invented certain new and useful Improvements in Sack-Fasteners; and I do declare the following to be a full, clear, and exact description of the invention, such as will enable others skilled in the art 10 to which it appertains to make and use the same.

My invention relates to improvements in metal sack fasteners and has for its object to provide an extremely simple, inexpensive, 15 and efficient fastener which can be easily applied and which may have such movement on the neck of the sack as to effectively tighten.

With the foregoing in view, the invention 20 resides in the novel article hereinafter described and claimed and shown in the accompanying drawing.

Figure 1 is a side elevation of the fastener applied to a sack.

Fig. 2 is a sectional view of the device in fastened position.

Fig. 3 is a view similar to Fig. 2, but showing the fastener released.

Fig. 4 is a perspective view.

In the drawing above briefly described, the numeral 1 designates a substantially circular frame having a U-shaped offset 2 at one side provided with parallel arms 3. This frame is constructed of a single metal 35 rod or a length of wire bent to proper shape, and in the smaller sizes of the device, the ends of the wire need not be connected, while in larger devices, said ends may be electrically welded or otherwise joined.

A fastening arm 4, preferably curved as shown, is formed of a length of wire or rod according to the size of the device, one end of said arm being bent to form an eye 5 pivotally surrounding the frame 1 opposite 40 the offset 2, and free to slide around said frame as seen in Fig. 1. The other end of arm 4 is bent to form a hook 6 for engage-

ment with a latch bar 7 which extends between the arms 3 of the U-shaped offset 2.

Bar 7 is formed of a rod or a piece of 50 wire and is bent into arch shape as shown, with its ends bent to form eyes 8 slidably surrounding the arms 3. When the latch bar 7 is in the position of Fig. 3, it allows the arm 4 to be swung to active position 55 around the sack neck as in Fig. 1, and said latch bar may then be slid inwardly and engaged with the hook 6. The fastener is thus tightly held in place to close the neck of the sack, and the eye 5 is free to slide around 60 the frame 1 so that the device may tighten after it is applied.

Release of the fastener is effected by pushing in on the arm 4, and sliding the latch bar 7 outwardly to release the hook 6. The 65 entire fastener may then be removed unless it is sewed to the sack as is desirable in the smaller sizes of the device.

The article may be easily and inexpensively manufactured and marketed and may 70 be used to great advantage, not only for sealing the neck of an ordinary sack, but for closing both ends of a double-ended sack, leaving sufficient material projecting beyond the fasteners to form hand holds by means 75 of which even very heavily loaded sacks may be easily handled.

I claim:

A sack fastener comprising a substantially circular frame having a U-shaped offset at 80 one side provided with parallel arms, an arched latch-bar of circular cross section having eyes at its ends slidably surrounding said arms, a longitudinally curved fastening arm of circular cross section having an eye 85 at one end pivotally surrounding the aforesaid frame and free to slide thereon to allow tightening of the fastening arm, the other end of said fastening arm having a hook engageable with said arched latch-bar. 90

In testimony whereof I have hereunto set my hand.

FREDERICK MARKWICK.
